FEEDING MECHANISM FOR SEWING MACHINES

David A. Graesser, Westfield, and Anthony J. Matuzas, Union, N. J., assignors to The Singer Manufacturing Company, Elizabeth, N. J., a corporation of New Jersey

Application March 24, 1948, Serial No. 16,796

17 Claims. (Cl. 112—210)

1 This invention relates to feeding mechanisms for sewing machines and it has as an object to provide an improved four-motioned feeding mechanism capable of being embodied in a relatively small cylindrical work-supporting arm.

Another object of the invention is to provide an improved four-motioned feeding mechanism of this nature in which the feed-driving mechanism and the feed-lift mechanism are so constructed and coordinated that the feed-dog is moved in a plane substantially parallel to the upper face of the throat-plate during its entire work-advancing stroke.

Another object of the invention is to provide an improved feeding mechanism in which the feed-bar is guided to move in vertical and horizontal planes without objectionable friction and in which the feed-drive and feed-lift mechanisms transmit their respective motions to the feed-bar without any angular distortion.

Another object of this invention is to provide a feeding mechanism having a feed-bar mounted for vertical and horizontal sliding movements and in which feed-lift and feed-drive movements are transmitted to said feed-bar by feed-lift and feed-drive rock-shafts through the medium of freely swinging vertically and horizontally disposed links, respectively.

A still further object of the invention is to provide a four-motioned feeding mechanism having improved manually actuated means for rendering the feeding mechanism ineffective to feed the work by dropping the feed-dog below the upper surface of the throat-plate to facilitate manual shifting of the work, as when embroidering, darning, etc.

Still another object of the invention is to provide, in a feeding mechanism having a feed-drive mechanism and a feed-lift mechanism, means for shifting the feed-dog to a position wholly below the upper surface of the throat-plate and for simultaneously therewith rendering the feed-lift mechanism ineffective to lift the feed-dog.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the drawings, Fig. 1 is a longitudinal vertical sectional view of a sewing machine embody-

2 ing the present invention, with certain ones of the parts shown in elevation.

Fig. 2 is an enlarged transverse vertical sectional view taken substantially on the line 2—2 of Fig. 1.

Fig. 3 is an enlarged central vertical sectional view of the free end portion of the work-supporting arm and the improved feeding mechanism therein, the loop-taker shaft and the loop-taker thereon being shown in elevation.

Fig. 4 is a bottom view of the machine shown in Fig. 1 with parts of the bed and the work-supporting arm broken away.

Figs. 5 and 6 are vertical sectional views taken substantially on the lines 5—5 and 6—6, respectively, of Fig. 1.

Fig. 7 is a detail vertical sectional view taken substantially on the line 7—7 of Fig. 1.

Fig. 8 is a detail sectional view taken substantially on the line 8—8 of Fig. 2.

Fig. 9 is a disassembled perspective view of certain elements of the present improved feeding mechanism, hereinafter to be described.

Figs. 10 and 11 are diagrammatic views, in two positions, of portions of the feed-lift mechanism and the means for dropping the work-engaging portion of the feed-dog below the upper surface of the throat-plate and for rendering the feed-lift mechanism ineffective to raise the feed-dog.

Referring more specifically to the drawings, the invention is disclosed as embodied in a sewing machine comprising a frame including an inverted box-like base 1 to which is secured a horizontally disposed cylindrical work-supporting arm 2. Secured upon the upper side of the base 1 is a sewing machine head comprising a standard 3, and an overhanging bracket-arm 4 which terminates in a vertically disposed bracket-arm head 5. Journaled horizontally in the bracket-arm in bearings 6 and 7 is a main or needle-bar driving shaft 8 to the rear end of which is secured a combined belt and hand wheel 9, by means of which the shaft is rotated from any suitable source of power. Mounted in bearings 10 and 11 in the bracket-arm head 5 is a reciprocating needle-bar 12 which carries, at its lower end, an eye-pointed thread-carrying needle 13. The needle-bar is reciprocated from the shaft 8 through the medium of a crank-disk 14 secured upon the shaft, a crank pin 15 carried by the disk, and a link 16 connecting the crank-pin with a stud carried by a collar 17 secured upon the needle-bar. The bracket-arm head also carries the usual spring-depressed presser-bar 18 to the lower end of which is secured a con-

55

ventional work-engaging presser-foot 19 adapted to cooperate with a feeding mechanism, herein-after described, to effect step-by-step feeding movements of the work.

Cooperating with the needle in the formation of stitches is a rotary loop-taker 20, which, in the present case, is of the rotary hook type having a needle-thread loop seizing beak 21. The loop-taker has journaled therein a bobbin-carrier 22 which is retained against rotation with the loop-taker by its engagement with stop shoulders, as 23, carried by the under side of a slotted throat-plate 24, secured to the upper portion of the arm 2, adjacent its free end.

The loop-taker 20 is secured upon one end of a rotary loop-taker shaft 25 journaled, adjacent its forward end, in a bearing member 26 secured in bearing bosses 2^a and 2^b depending from the upper wall of the arm 2 and, at its rear end, in a bearing 27 provided by the base 1. The loop-taker shaft 25 is rotated from the main shaft 8 through the medium of a pair of bevel gears 28, 29, which drive a shaft 30 journaled vertically in the standard 3, and a second pair of bevel gears 31, 32 of which the former is secured upon the shaft 30 and the latter upon the loop-taker shaft 25. The ratios of the gears 28, 29 and 31, 32 are such that the loop-taker shaft and the loop-taker carried thereby are given two rotations for each rotation of the main shaft 8 and consequently two rotations for each reciprocation of the needle-bar.

An improved four-motioned feeding mechanism, now to be described, is provided for advancing the work once for each reciprocation of the needle. This feeding mechanism comprises a feed-dog 33 having serrated work-engaging portions which operate through slots in the throat-plate 24. The feed-dog is secured, as by screws 34, to the flat upper surface 35^a of a vertically disposed ring-like supporting member 35, hereinafter called the feed-bar, which surrounds the bearing member 26 and is given rising and falling movements from a feed-lift rock-shaft 36 journaled lengthwise within the work-supporting arm 2 on pintles 37 and 38 secured in the machine frame. The feed-bar 35 and the feed-dog 33 carried thereby are also given feed and return movements, from a feed-drive rock-shaft 39 journaled lengthwise within the arm 2 on pintles 40 and 41, also secured in the machine frame.

Secured upon the main shaft 8 is a feed-drive cam 42 which rotates between the spaced walls 43^a of a fork 43 formed at the upper end of a pitman 44. At its lower end, the pitman 44 is pivotally connected, at 45, to one end of a rock-arm 46, the other end of which is secured upon the feed-drive rock-shaft 39, as by pinch joint 47. Adjacent its upper end, the pitman 44 carries a roller stud 48 which tracks a channel 49^a formed in a guide-block 49 mounted, for angular adjustment, on a screw stud 50 supported by the standard 3. The block 49 carries a handle 51 which projects through a slot 3^a in the forward wall of the standard 3. With the parts in the positions shown in Fig. 2, back and forth oscillation of the pitman 44, about the pivot 45, by the cam 42, will cause the roller stud 48 to ride up and down in the inclined channel 49^a thereby translating the back and forth movements of the pitman into endwise reciprocations. These endwise movements of the pitman cause the rock-arm 46 and the feed-drive shaft 39 to be oscillated about the axis of that shaft. These oscillations transmit feed and return movements to the feed-

bar 35 and the feed-dog 24 carried thereby, by mechanism hereinafter described. The portion of the feed-drive mechanism above described is conventional and forms no part of this invention. As is well understood, the amount of endwise movement transmitted to the pitman 44 by the stud 48 and block 49 and consequently the length of feed stroke of the feed-dog 24, is dependent upon the angular setting of the block. By shifting the handle 51 upwardly from its lowermost position to a mid-position the feed stroke may be reduced from maximum to zero. Likewise by shifting the handle upwardly above its mid-position the angular position of the block 49 and channel 49^a may be inclined in the direction opposite to that shown in Fig. 2 thereby effecting a reverse feed.

The means for giving to the feed-bar 35 and feed-dog 24 their rising and falling movements, in synchronism with their feed and return movements, comprises an eccentric 52 secured upon the main shaft 8, adjacent the feed-drive cam 42. This eccentric is surrounded by the strap end 53^a of a pitman 53. At its lower end, the pitman 53 is pivotally connected, by a stud 54, to the upper end of a link 55, the lower end of which is pivoted, by stud screw 56, to the free end of a rock-arm 57 secured, by pinch joint 58, on the feed-lift rock-shaft 36. The stud 54 carries a roller 59 which tracks a channel 60^a formed in a tiltable guide-block 60 integral with a shank 61 journaled in boss 62 depending from the upper wall of the base 1. The shank 61 and block 60 are frictionally retained in their adjusted positions by a friction-washer 63 interposed between the boss 62 and a nut 64 threaded on the shank. A hand lever 65 secured on the shank 61, between the nut 64 and a second nut 66, serves as means for angularly adjusting the block 60.

With the parts in the positions illustrated in Figs. 1, 2 and 10, endwise reciprocations of the pitman 53, under the influence of the eccentric 52, causes the roller 59 to ride up and down in the channel 60^a at an angle of approximately 30 degrees to the vertical, as represented by the arrow *a* in Fig. 10. These movements shift the link 55 endwise, as represented by arrow *b*, which, in turn, oscillate the rock-arm 57 and feed-lift rock-shaft 36, as indicated by the arrow *c*.

From the foregoing, it will be understood that, with the parts in the positions shown in Figs. 1, 2 and 10, rotation of the shaft 8 will effect oscillatory motions in the feed-lift shaft 36 and the feed-drive shaft 39. These oscillatory motions are transmitted to the feed-bar 35, and to the feed-dog 33 carried thereby, through the medium of directly acting endwise movable links which give to the feed-bar vertical rising and falling movements and horizontal feed and return movements.

As shown most clearly in Figs. 1, 3 and 9, the stationary bearing member 26, for the loop-taker shaft 25, is formed, at one end, with a stationary guide member in the form of a disk or flange 26^a provided with diametrically opposed vertically arranged slots 26^b and 26^c and a flattened and beveled upper edge 26^d. Surrounding the bearing member 26, and in engagement with the rear face of the disk 26^a, is a flat ring-like slide member 67 having forwardly projecting lugs 67^b, 67^c which are slidably received in the slots 26^b and 26^c, respectively, in the disk 26^a. The slide member 67 is formed with a relatively large central aperture 67^d which affords sufficient clearance 75 around the bearing member 26 to permit the

slide member to partake of the vertical movements of the feed-bar. At its rear side, the slide member 67 carries lugs 67^e and 67^f which are slidably fitted within horizontally arranged slide-ways 35^e and 35^f, respectively, formed in the feed-bar 35. The feed-bar 35 also has a relatively large central aperture 35^d which affords sufficient clearance around the bearing member 26 to permit the feed-bar to be given vertical feed-lift and horizontal feed-drive movements. The forward vertical face of the feed-bar is held in contact with the rear vertical face of the slide member 67 by a stationary guide plate 68 which surrounds the bearing member 26 and which is held in contact with the rear face of the feed-bar by a washer 69 and a snap ring 70, which latter is fitted into an annular groove 71 in the bearing member 26. A pin 72, secured in the plate 68 and projecting therefrom and fitted into a drill hole 73 in the member 35, anchors the plate against rotation about that member.

Secured in the feed-bar 35, and projecting rearwardly therefrom, are two horizontally disposed pins 74 and 75 connected, respectively, to the feed-lift and feed-drive mechanisms. The pin 74 passes through an aperture 68^a in the plate 68. The upper edge of the plate 68 is formed with a cut-out 68^b which affords clearance for the pin 75. Journalized on the pin 74 is the lower end of a vertically disposed feed-lift link 76, the upper end of which is pivotally connected, by a bolt 77, with the free end 78^a of a rock-arm 78 integral with the feed-lift rock-shaft 36.

The pin 75, which projects from the feed-bar 35, has pivotally mounted thereon one end of a horizontally disposed feed-drive link 79 the other end of which is pivotally connected, by a bolt 80 with the upper free end 81^a of an arcuate rock-arm 81 integral with the feed-drive rock-shaft 39.

From the foregoing it will be understood that the feed-bar 35 and the slide member 67 are mounted for simultaneous vertical movement between the flange 26^a and the plate 68, while the feed-bar is mounted for independent horizontal movement between the slide member 67 and the plate 68. The feed-lift link 76 and the feed-drive link 79 are connected to the feed-bar 35, and transmit feed-lift and feed-drive movements directly to the feed-bar without any binding or any angular distortion. Inasmuch as the member 67 is free to float with the feed-bar the vertical and horizontal guideways 26^b, 26^c and 35^e, 35^f serve to orient the feed-bar but in no way determine the path of movement of a point on the feed-bar, this being directly determined by the characteristics of the linkage and the actuating means therefor.

The means for dropping the feed-dog and for maintaining the work-engaging teeth thereof below the work-supporting surface of the throat-plate will now be described. As hereinbefore stated, with the parts in the positions illustrated in Figs. 1, 2 and 10, rotation of the main shaft 8 and the eccentric 52 thereon will effect endwise reciprocations of the pitman 53 which, in turn, through the guide block 60, link 55 and rock-arm 57, will oscillate the feed-lift rock-shaft 36 and cause the rock-arm 78 and link 76 to raise and lower the feed-bar 35 and the feed-dog 33 secured thereto. When it is desired to drop the feed-dog and to discontinue its rising and falling movements, the operator shifts the hand lever 65 rearwardly to the position illustrated in Figs. 7 and 11. This causes the guide-block 60 to be

turned about its pivot 61, which, as shown most clearly by Figs. 8 and 10, is located more closely to the upper end of the block 60 than to the lower end thereof. This turning movement of the block 60 shifts the link 55 upwardly to the position shown in full lines in Fig. 11. This upward endwise movement of the link 55 turns the rock-arm 57, rock-shaft 36 and rock-arm 78 clockwise about the axis of the rock-shaft thereby dropping the link 76, feed-bar 35 and feed-dog 33 from the position shown in dotted lines in Fig. 11 to the position shown in full lines. The feed-bar and the feed-dog are maintained in this lowered position so long as the hand lever 65 is retained in the position illustrated in Figs. 7 and 11. In this position of the parts, endwise reciprocation of the pitman 53, under the influence of the eccentric 52, causes the stud 59 to be shifted back and forth in the channel 64^a in the block 60, as represented by the arrow a'. Inasmuch as this movement is of limited extent and is substantially tangential to an arc swung from the axis of the pivot screw 56, the link 55 swings idly about the screw 56, as indicated by the arrow b' and no appreciable lifting movement is transmitted to the feed-bar 35 and feed-dog 33.

Having thus set forth the nature of the invention, what we claim herein is:

1. A feeding mechanism for sewing machines comprising a vertically disposed feed-bar; a feed-dog secured to said feed-bar; means connected directly to said feed-bar for supporting said feed-bar and for giving to it feed-drive and feed-lift movements; a guide member engaging one face of said feed-bar; and an interfitting sliding connection between said feed-bar and said member for guiding said feed-bar in its horizontal feed and return movements.
2. A feeding mechanism for sewing machines comprising a rotary drive shaft; a vertically disposed feed-bar; a feed-dog secured to said feed-bar; means actuated by said drive shaft and connected directly to said feed-bar for supporting said feed-bar and for giving to it feed-drive and feed-lift movements; guide members engaging the opposite faces of said feed-bar; and an interfitting sliding connection between said feed-bar and one of said members for guiding said feed-bar in its horizontal feed and return movements.
3. A feeding mechanism for sewing machines comprising a rotary drive shaft; a vertically disposed feed-bar; a feed-dog secured to said feed-bar; means actuated by said drive shaft and connected directly to said feed-bar for supporting said feed-bar and for giving to it feed-drive and feed-lift movements; a stationary guide member horizontally spaced from said feed-bar; a movable guide member disposed between the opposed faces of said feed-bar and said stationary guide member; an interfitting sliding connection between said movable guide member and said stationary guide member for constraining said movable guide member to move in a predetermined right-line direction; and an interfitting sliding connection between said movable guide member and said feed-bar for constraining said feed-bar to move relative to said movable guide member in a predetermined right-line direction which is disposed at right angles to the first mentioned direction.
4. A feeding mechanism for sewing machines comprising a rotary drive shaft; a vertically disposed feed-bar; a feed-dog secured to said feed-bar; means including horizontally and vertically

disposed links actuated from said drive shaft and connected to said feed-bar for supporting said feed-bar and for giving to it feed-drive and feed-lift movements; a stationary guide member horizontally spaced from said feed-bar; a movable guide member disposed between the opposed faces of said feed-bar and said stationary guide member; an interfitting sliding connection between said movable guide member and said stationary guide member for constraining said movable guide member to move in a predetermined right-line direction; and an interfitting sliding connection between said movable guide member and said feed-bar for constraining said feed-bar to move relative to said movable guide member in a predetermined right-line direction which is disposed at right angles to the first mentioned direction.

5. A feeding mechanism for sewing machines comprising a rotary drive shaft; a feed-bar having a horizontally disposed guide surface; a feed-dog secured to said feed-bar; means actuated by said drive shaft and connected to said feed-bar for supporting said feed-bar and for giving to it feed-drive and feed-lift movements; a stationary guide plate engaging one face of said feed-bar; and a slide member engaging the opposite face of said feed-bar and having a portion complementary to the guide surface of said feed-bar for guiding said feed-bar in its horizontal feed and return movements.

6. A feeding mechanism for sewing machines comprising a rotary drive shaft; a feed-bar having horizontally disposed guide surfaces; a feed-dog secured to said feed-bar; means actuated by said drive shaft and connected directly to said feed-bar for giving to the feed-bar its feed-drive and feed-lift movements; a guide plate engaging one face of said feed-bar; a slide member engaging the opposite face of said feed-bar; and horizontally disposed guide surfaces provided by said slide member and engaging the guide surfaces of said feed-bar to guide the feed-bar during its feed and return movements.

7. A feeding mechanism for sewing machines comprising a rotary drive shaft; a vertically disposed feed-bar; a feed-dog secured to said feed-bar; means actuated by said drive shaft and connected directly with said feed-bar for supporting the feed-bar and for giving to it feed-drive and feed-lift movements; first and second guide members having their inner faces engaging the opposite faces of said feed-bar, the first one of said members being stationary and the second being slidably connected horizontally to said feed-bar to guide the feed-bar in its horizontal movements and to cause said second guide member to partake of the vertical movements of the feed-bar; and vertically disposed guide means engaging said second guide member to guide said second guide member in its vertical movements with the feed-bar.

8. A feeding mechanism for sewing machines comprising a rotary drive shaft; a vertically disposed feed-bar having a horizontal slideway; a feed-dog secured to said feed-bar; means including vertically and horizontally disposed endwise movable links actuated by said drive shaft and connected directly with said feed-bar for supporting the feed-bar and for giving to it feed-lift and feed-drive movements, respectively; first and second guide members having their inner faces engaging the opposite faces of said feed-bar, the first one of said members being stationary and the second being provided with a

horizontally disposed guide rib fitted within the slideway in said feed-bar to guide the feed-bar in its horizontal movements and to cause said second guide member to partake of the vertical movements of the feed-bar; and vertically disposed guide means engaging said second guide member to guide said second guide member in its vertical movements with the feed-bar.

9. A feeding mechanism for sewing machines comprising a feed-drive rock-shaft; a first rock-arm on said rock-shaft; a feed-lift rock-shaft; a second rock-arm on said feed-lift rock-shaft; a vertically disposed feed-bar; a feed-dog secured to said feed-bar; a horizontally disposed link connecting said first rock-arm with said feed-bar; a vertically disposed link connecting said second rock-arm with said feed-bar; a movable guide member connected with said feed-bar so that relative movements therebetween are confined to a right-line direction; and a stationary guide member connected with said movable guide member so that the movements of said movable guide member are confined to a right-line direction which is disposed at right angles to the first mentioned direction.

10. A feeding mechanism for a sewing machine having a substantially cylindrical work-supporting arm, comprising a feed-drive rock-shaft journaled in the lower portion of said work-supporting arm and substantially mid-way between the side walls thereof; a first rock-arm on said rock-shaft and having its free end located in the upper portion of said work-supporting arm; a feed-lift rock-shaft; a second rock-arm on said feed-lift rock-shaft; a vertically disposed feed-bar; a feed-dog secured to said feed-bar; a horizontally disposed link connecting the free end of said first rock-arm with said feed-bar; a vertically disposed link connected at its upper end to the free end of said second rock-arm and at its lower end to said feed-bar; guide members engaging the opposite faces of said feed-bar, one of said guide members being constrained to move vertically; and an interfitting sliding connection between said feed-bar and said one of said members for guiding said feed-bar in its horizontal feed and return movements.

11. In a sewing machine, in combination, a substantially cylindrical work-supporting arm; a loop-taker shaft bearing secured within said arm and comprising a cylindrical portion extending lengthwise of said arm substantially centrally thereof and a transverse flange at one end of said cylindrical portion; a loop-taker shaft journaled in said bearing; a vertically disposed feed-bar surrounding said shaft bearing; a feed-dog carried by said feed-bar; a guide member surrounding said shaft bearing and secured thereto against rotation, said guide member bearing against one face of said feed-bar; a second guide member mounted for vertical movement on the flange portion of said shaft bearing and engaging the other face of said feed-bar; and a horizontally disposed interfitting guiding connection between said second guide member and said feed-bar.

12. In a sewing machine, in combination, a substantially cylindrical work-supporting arm; a loop-taker shaft bearing secured within said arm and comprising a cylindrical portion extending lengthwise of said arm substantially centrally thereof and a transverse flange at one end of said cylindrical portion said flange being provided with oppositely extending vertically disposed radial slots; a loop-taker shaft journaled in said bearing; a vertically disposed ring-like feed-bar

surrounding said shaft bearing; a feed-dog carried by said feed-bar; a plate-like guide member surrounding said shaft bearing and secured thereto against rotation, said guide member bearing against one face of said feed-bar; a second guide member having projecting lugs slidingly fitted within the slots in the flange portion of said shaft bearing, said second guide member engaging the other face of said feed-bar; and a horizontally disposed interfitting guiding connection between said second guide member and said feed-bar.

13. In a sewing machine, in combination, a substantially cylindrical work-supporting arm; a loop-taker shaft bearing secured within said arm and comprising a cylindrical portion extending lengthwise of said arm substantially centrally thereof and a transverse flange at one end of said cylindrical portion said flange being provided with oppositely extending vertically disposed radial slots; a loop-taker shaft journaled in said bearing; a vertically disposed feed-bar surrounding said shaft bearing and provided with a horizontally disposed slideway; a feed-dog carried by said feed-bar; a vertically disposed guide member surrounding said shaft bearing and secured thereto against rotation, said guide member engaging the rear face of said feed-bar; a second guide member engaging the forward face of said feed-bar and having at one face a pair of projecting lugs slidingly fitted within the slots in the flange portion of said shaft bearing and at its opposite face a pair of projecting lugs fitted within the slideway in said feed-bar; and means directly engaging said feed-bar for giving to it vertical and horizontal movements.

14. A sewing machine combining a frame; a rotary drive shaft journaled therein; a slotted throat-plate carried by said frame; a work-feeding mechanism comprising a four-motioned feed-bar; a feed-dog secured to said feed-bar and having serrated portions normally operating through the slots in the throat-plate; means actuated from said drive-shaft for giving to said feed-bar feed and return movements; feed-lifting mechanism actuated by said drive shaft for giving to said feed-bar up and down movements in synchronism with its feed and return movements, said feed-lifting means comprising an actuating element on said drive shaft; a pitman connected to said element for endwise reciprocation thereby; a feed-lift rock-shaft connected with said feed-bar; connecting means between said pitman and said rock-shaft for transmitting to the rock-shaft oscillatory motions from the endwise reciprocations of said pitman; and manually shiftable means for rendering said connecting means ineffective to oscillate said rock-shaft and for simultaneously therewith shifting said feed-dog to a position wholly below the upper surface of the throat-plate.

15. A sewing machine combining a frame; a rotary drive shaft journaled therein, a work-feeding mechanism comprising a four-motioned feed-bar; a feed-dog carried by said feed-bar; means actuated from said drive shaft for giving to said feed-bar feed and return movements; feed-lift-

ing mechanism actuated by said drive shaft for giving to said feed-bar up and down movements in synchronism with its feed and return movements, said feed-lifting means comprising an actuating element on said drive shaft; a pitman connected to said element for endwise reciprocation thereby; a feed-lift rock-shaft connected with said feed-bar; connecting means between said pitman and said rock-shaft comprising a rock-arm on said rock-shaft; a link pivotally connected at its lower end to the free end of said rock-arm and at its upper end to the lower end of said pitman; guide means acting on the lower end of said pitman to cause it to move in a path to transmit endwise movements to said link thereby to cause it to effect oscillation of said feed-lift rock-shaft; and means to vary the guide means to cause the lower end of the pitman to move in a path substantially tangent to an arc swung from the lower pivotal connection of said link, thereby to discontinue the oscillation of said feed-lift rock-shaft.

16. A sewing machine as set forth in claim 15 in which the guide means which acts on the lower end of the pitman to cause it to move in a path to transmit endwise movements to the link comprises a pivotally mounted guide-block having a slideway and a stud on the lower end of said pitman which tracks said slideway, and in which the means for varying the guide means to cause the lower end of the pitman to move in a path substantially tangent to an arc swung from the lower pivotal connection of the link comprises a manually actuatable hand lever secured to said guide-block and readily accessible to the machine operator.

17. A sewing machine as set forth in claim 15 in which the means which acts on the lower end of the pitman to cause it to move in a path to transmit endwise movement to the link comprises a pivotally mounted guide-block having a slideway, and a stud on the lower end of said pitman which tracks said slideway and is maintained eccentric to the pivot of the guide-block; and in which a hand lever is secured to said guide-block and serves as means to shift the guide-block to a position in which it renders the pitman ineffective to transmit oscillations to said feed-lift rock-shaft and simultaneously therewith shifts said link endwise thereby to turn said feed-lift rock-shaft to cause it to lower the upper portion of said feed-dog below the upper surface of the throat-plate.
